Achilles C. Gough

UNITED STATES PATENT OFFICE.

ACHILLES CALLOWAY GOUGH, OF POCATELLO, IDAHO.

ELECTRIC CURLING-IRON.

1,056,987.

Specification of Letters Patent.

Patented Mar. 25, 1913.

Application filed July 15, 1912. Serial No. 709,596.

To all whom it may concern:

Be it known that I, ACHILLES C. GOUGH, a citizen of the United States, residing at Pocatello, in the county of Bannock and State of Idaho, have invented certain new and useful Improvements in Electric Curling-Irons; and I do hereby declare the following to be a full, clear, and exact description of the invention, such as will enable others skilled in the art to which it appertains to make and use the same.

This invention relates to improvements in curling-irons, and particularly to what are known as electric curling-irons.

The object in view is to provide new and improved means for curling or waving the hair in such manner that the hair when dressed with this appliance will have a curly or wavy appearance, more nearly approaching that of naturally curly or wavy hair.

A further object of the invention is to provide improved means for maintaining the working members of a curling iron at the proper temperature, for curling or waving the hair, by the heating effect of an electric current.

Another object of the invention is to provide an improved heating element, to be contained within each working member of a curling-iron, the resistance of said element or elements to be such that the emission will equal the inflow of energy at a predetermined temperature.

With these and other objects in view, the invention comprises certain novel principles, constructions, and arrangement of parts as will be hereinafter more fully described and claimed.

In the accompanying drawings: Figure 1 is a vertical sectional view through an embodiment of the invention, certain parts being shown in elevation. Fig. 2 is an enlarged view of a heating element, partly in section at the ends, disclosing the construction of said heating element. Fig. 3 is a cross section through Fig. 1, approximately on line A—B. Fig. 4 is a circuit diagram showing a specific method of connecting the heating elements to the source of current.

Fig. 5 is a vertical view of the curling-iron disclosing the method of applying said iron to the hair for producing the effect of naturally wavy or curly hair.

Corresponding parts in all the figures are denoted by the same reference characters.

In forming a device embodying the inven-

tion, the heating elements of the same may be connected through a suitable cord and removable plug to a standard incandescent lamp circuit using either alternating or direct current.

In order that the invention may be more clearly understood, an embodiment of the same is shown in the accompanying drawings.

In the drawings, 1 and 2 are seamless steel tubes closed at one end and secured nearly parallel relatively to one another, by being brazed or welded to the steel cup, 12. The working members, 1 and 2, and the steel cup 12 are rigidly supported by a wood handle, 10. In order that any portion of hair, 26, should not have a tendency to slip off the end of one working member while being placed around the other working member, said working members, 1 and 2, may have the closed ends turned outwardly away from each other, as shown at 13 and 14.

5 and 6 are very small metal rods covered, heavily, with fire-proof insulating material forming, respectively, the cores, 15 and 16. The resistance wires, 3 and 4, are supported, respectively, by the cores, 15 and 16, and the resistance wires may or may not be covered with fire-proof insulating material, said resistance wires being electrically connected at the outer ends to the central metal rods after the manner shown at 25, Fig. 2. Thus, one terminal 90 of the flexible cord, 9, is divided into two parts, secured and electrically connected to the two central metal rods, 5 and 6, respectively, as shown, at 7 and 8; the other terminal of cord, 9, being secured and electrically connected to the resistance wires, 3 and 4, as shown, respectively, at 24 and 28, Fig. 4. The resistance wires may be electrically connected in series or parallel. The circuit diagram, Fig. 4, shows parallel connection, 100 the rods 5 and 6 being electrically connected to the resistance wires, 3 and 4, as shown, respectively, at 25 and 27, Fig. 4. Then, in the circuit diagram, Fig. 4, 9 represents a flexible cord, 21 represents a removable plug 105 and 29 represents a standard incandescent lamp socket; the electrical circuit being completed through the rods, 5 and 6, and the resistance wires, 3 and 4. The heating elements proper are further wrapped by 110 wires covered with fire-proof insulating material, these binding wires are applied

near the ends and near the middle of the heating element, as shown at 17, 18, 19, 20, 22, and 23, these wires, 17, 18, etc., serve the dual purpose of binding 5 the resistance wires, 3 and 4, more securely upon the cores 15 and 16, and that of retaining the resistance elements in their proper positions within the steel tubes.

What I claim is:

- 10 1. In a device of the character described, the combination of a casing, heating elements seated therein, and means spacing said heating elements from said casing comprising wire-wrapped end and center sectional bearings.
- 15 2. In a device of the character described, the combination with a casing, of heating

devices having internal, metallic and electric connecting elements, fire-proof insulation insulating said elements, wire heat-generating coils encircling said insulation and connected to said internal, metallic, electric connecting elements at one end, and closely wrapped, insulated wire supports at the end and center portions of said heating devices, 20 to support said heating devices into spaced 25 position to said casing.

In testimony whereof I have affixed my signature in the presence of two witnesses.

ACHILLES CALLOWAY GOUGH.
